(57) **CLAIM**

The ornamental design for a global navigation satellite system receiver and handheld receptacle therefor as shown and described.

DESCRIPTION

FIG. 1 is a bottom view of a global navigation satellite system receiver and handheld receptacle therefor;

FIG. 2 is a top view of the global navigation satellite system receiver and handheld receptacle therefor of FIG. 1; FIG. 3 is a rear elevation view of one side of the global navigation satellite system receiver and handheld receptacle therefor of FIG. 1;

FIG. 4 is a front elevation view of the other side of the global navigation satellite system receiver and handheld receptacle therefor of FIG. 1;

FIG. 5 is a right elevation view of the global navigation satellite system receiver and handheld receptacle therefor of FIG. 1;

FIG. 6 is a left plan view of the global navigation satellite system receiver and handheld receptacle therefor of FIG. 1; FIG. 7 is a perspective view from the front of a global navigation satellite system receiver and handheld receptacle therefor;

FIG. 8 is another perspective view of the global navigation satellite system receiver and handheld receptacle therefor of FIG. 7;

FIG. 9 is an exploded view of a bottom view of the global navigation satellite system receiver and handheld receptacle therefor of FIG. 1 in which the global navigation satellite system receiver is separate from the handheld receptacle therefor;

FIG. 10 is an exploded view of the top view of the global navigation satellite system receiver and handheld receptacle therefor of FIG. 2 in which the global navigation satellite system receiver is separate from the handheld receptacle therefor;

FIG. 11 is an exploded view of a rear elevation view of the global navigation satellite system receiver and handheld receptacle therefor of FIG. 3 in which the global navigation satellite system receiver is separate from the handheld receptacle therefor;

FIG. 12 is an exploded view of a side elevation view of the other side of the top plan view of the global navigation satellite system receiver and handheld receptacle therefor of FIG. 4 in which the global navigation satellite system receiver is separate from the handheld receptacle therefor.

FIG. 13 is an exploded view of a right elevation view of the global navigation satellite system receiver and handheld receptacle therefor of FIG. 5 in which the global navigation satellite system receiver is separate from the handheld receptacle therefor.

(Continued)

FIG. 14 is an exploded view of a left plan view of the global navigation satellite system receiver and handheld receptacle therefor of FIG. 6 in which the global navigation satellite system receiver is separate from the handheld receptacle therefor.

FIG. 15 is an exploded view of a perspective view from the front of the global navigation satellite system receiver and handheld receptacle therefor of FIG. 7 in which the global navigation satellite system receiver is separate from the handheld receptacle therefor; and,

FIG. 16 is an exploded view of another perspective view of the global navigation satellite system receiver and handheld receptacle therefor of FIG. 8 in which the global navigation satellite system receiver is separate from the handheld receptacle therefor.

The portions shown in broken lines are for illustrative purposes only and form no part of the design.
